UNITED STATES PATENT OFFICE

WILLIAM A. MURRAY, SR., OF CINCINNATI, OHIO, ASSIGNOR TO THE WILLIAM A. MURRAY SPRING COMPANY, OF CINCINNATI, OHIO, A CORPORATION OF OHIO

SPRING SEAT FOR VEHICLES

Application filed July 15, 1929. Serial No. 378,224.

This invention relates to spring seats that comprise an upper and a lower wire frame, cross strips secured to the lower frame, coiled springs mounted upon the cross strips and 5 clips connecting the upper coils of the springs with the upper frame.

The object of my invention is to provide a means for preventing the sagging and bending of the front member of the upper frame 10 and for preventing the clips, that connect said upper member with the coils, from cutting the adjacent superposed upholstering.

Several expedients have been used by manufacturers of spring seats, to overcome 15 the aforesaid defects of this character of seat. One of such expedients consisted of brace wires extending from the front member of the top wire to the rear member of the lower wire. Other means were wires connecting 20 the front and rear members of the top frame and clips connecting these wires to the top coils of adjacent springs. However, these expedients have proved unsatisfactory in use because the wires bend and no protection is 25 afforded the upholstering against the abrasive effects of the clips that connect the top coils to the front member of the top frame.

The means embodying my invention comprise a strip of sheet metal, folded longitudinally, so as to form a sleeve, which is 30 U-shaped in cross section and which embraces the front member of the top frame, the clips that connect the top coils of the springs to the frame, and the front portions of the top 35 coils and is clamped about said clips and said adjacent portions of the top coils.

When persons seat themselves upon an automobile cushion their weight is exerted in a rearward and downward direction against 40 the cushion, along the front edge. This not only puts a strain upon the front member of the top frame but forces the upholstering material violently against the uneven surfaces, made by the clips, of the coils and the front 45 member of the top frame.

The continuous sleeve of this invention which embraces the front top wire, the front part of the top coils and the clips and is 50 clamped thereon, firmly braces these parts together besides giving its added strength to

the front member of the top frame. Moreover, the continuous sleeve presents a smooth surface to the upholstering, which consequently is not torn nor abraded by any rough edges.

With reference to the drawings:

Fig. 1 is a front elevational view of an upholstered spring seat structure embodying the means of this invention.

Fig. 2 is a view taken on line 2—2 of Fig. 1. 60

Fig. 3 is a view taken on line 3—3 of Fig. 1, parts being broken away.

Fig. 4 is a detail view of the means of this invention.

The seat 8 has the upper and lower continuous wire frames 9 and 10, respectively. Cross strips 11 are secured upon frame 10, extending from the front to the rear thereof. Coiled springs 12 are secured along strips 11 by suitable means, such as by lugs or eyelets 70 13 struck upwardly from the body of strips 11 and adapted to receive and bind the lowermost coils of the springs. The springs 12, adjacent the front of the seat contain a greater number of coils than those adjacent 75 the rear, by which means the upper frame 9 is angularly disposed relative to lower frame 10. The springs 12 which are adjacent the members of the top frame 9 have their top coils secured to frame 9 by means of clips 14. Suitable cross wiring connects the top coils 80 of the springs and completes a supporting area for the upholstering. This cross wiring, inasmuch as it in no way affects the present invention, is not shown in the drawings. 85

A sleeve 15 is positioned along the front member of frame 9, enclosing the series of clips and coils secured to the frame. Sleeve 15 comprises a strip, preferably of metal, bent longitudinally adjacent its mid point to form 90 a member substantially U shaped in cross section. Upper side 16 of sleeve 15 is of greater width than the under side 17 and both of the sides 16 and 17 are of greater width than clips 14. Hence, when sleeve 15 is positioned along 95 the front portion of frame 9, sides 16 and 17 pass beyond and completely cover the front member of frame 9, the clips 14 and the portions of the coils 12 enclosed thereby. The longitudinal edges of sides 16 and 17 are now 100

pressed toward one another to secure sleeve 15 to the frame 9. This formation results in the enlarged portions 18 enclosing the frame member, clips and coils and the depressed portions 19 enclosing only the frame member and along which portions 19 the edges 16 and 17 of sleeve 15 may be pressed into firm contacting or near-contacting relationship whereby movement and withdrawal of sleeve 15 are prevented. The under lip 20 of each portion 18 may be further turned inwardly to bear against clip 14 and the coil portions immediately adjacent thereto, or it may be left straight as indicated in dotted lines (Fig. 3). The fact that side 16 extends over and beyond side 17 of sleeve 15 effectually prevents any possibility of the upholstering or strands thereof, catching upon the members enclosed by the sleeve 15. Thus there is provided a channel member presenting a smooth, slanting surface upon which the upholstering can move without interference and at the same time there is provided a double strip materially strengthening that portion of a seat which is subject to the greatest strains.

Whilst I have described my invention as applied to a certain form of spring-seat construction, I do not wish it to be limited to that form of seat construction.

What is claimed is:

1. A spring seat comprising a top wire frame, springs with top coils adjacent the front member of the top frame, clips connecting the top coils with said member and a metal sleeve embracing said front member and the clips that connect said front member with the top coils.

2. A spring seat comprising a top wire frame, springs with top coils adjacent to the front member of the wire frame, clips connecting the top coils to said front member and a strip of metal folded to form a sleeve U shaped in cross section and embracing the front member and the clips and forming a smooth contact for the upholstering.

In testimony whereof, I have hereunto subscribed my name this 6th day of July, 1929.

WILLIAM A. MURRAY, SR.
